UNITED STATES PATENT OFFICE.

HOMER GRIMES AND HOLLIE B. STOVER, OF CENTRALIA, ILLINOIS.

VENEER TILE.

Application filed August 30, 1928. Serial No. 303,026.

The invention relates to a new and improved tile facing or veneer for new and old walls, constructed from any desired material or materials to simulate bricks.

5 It is one object of the invention to provide for the necessary weather excluding overlap of the separate tiles with portions thereof disposed at an incline similar to shingles, yet with their brick simulating portions 10 truly vertical at their exposed faces.

It is another object of the invention to provide tiles of such shapes that all conditions encountered, may be readily met.

15 With the foregoing in view, the invention resides in the novel subject matter herein-after described and claimed, the description being accomplished by reference to the accompanying drawings.

20 Fig. 1 is an elevation partly in vertical section showing a portion of a wall with an internal angle at the left and an external angle at the right.

Fig. 2 is a horizontal sectional view on line 2—2 of Fig. 1, and this view also shows 25 the line 1—1 upon which Fig. 1 is cut.

Fig. 3 is a view similar to Fig. 1 but showing an internal angle or corner at the right and an external angle or corner at the left, this view being cut on line 3—3 of Fig. 4.

30 Fig. 4 is a horizontal sectional view on the correspondingly numbered line of Fig. 3.

Figs. 5, 6 and 7 are respectively a front elevation, a vertical section and a perspective view of the tile A, Fig. 6 being cut on 35 line 6—6 of Fig. 5.

Figs. 8, 9 and 10 are respectively a front elevation, a vertical section and a perspective view of the tile B, Fig. 9 being cut on line 9—9 of Fig. 8.

40 Figs. 11, 12 and 13 are respectively a front elevation, an end elevation and a perspective view of the tile C.

Figs. 14, 15 and 16 disclose respectively a side elevation, an end elevation and a perspective view of the tile D.

Figs. 17, 18 and 19 illustrate a side elevation, an end elevation and a perspective view of the unit E.

50 Figs. 20 and 21 are respectively a front elevation and a perspective view of the tile F.

With the tiles in Figs. 5 to 21, practically all situations encountered in veneering a new or old wall with the tile facing, may be met, and while the descriptive matter will be limited to these tiles, it is to be understood that

others could be produced to cope with any unusual situation. Moreover, while we will not herein refer to any specific dimensions, it is to be understood that any or all of the 60 tiles may be of any desired size or sizes and that some of these tiles may be furnished in different sizes for filling in spaces either too short or too long for the use of a tile of standard length.

65 In Figs. 5 to 21, the construction of the tiles A, B, C, D, E and F have been shown in detail and Figs. 1, 2, 3 and 4 will give examples of the ways in which they are used, the same reference characters being employed on the tiles in these assembled views. Thus, the functions performed by the several 70 tiles may be readily understood without specific explanation.

75 The tile A embodies a lower brick-simulating portion 22 gradually thickened from its lower to its upper edge, a mortar-simulating step 23 at the upper edge and at one end only of said brick-simulating portion 22, and a flat upstanding attaching flange 80 24 which is rearwardly off-set from the step 23. This flange has its front side parallel with its rear side and the latter is in the same plane with the rear side of the brick-simulating portion 22. Both ends of the 85 tile A are at substantially right angles to the lower edge of the portion 22, although one or both of these ends may be slanted somewhat at the ends of the flange 24, as denoted at 25, to give ample clearance between 90 flanges of adjacent tiles and permit the latter to be angled to slight extents to compensate for any inaccuracies, etc.

When the tiles A are applied, their rear 95 sides and their flanges 24 occupy inclined positions as will be clear from Fig. 3 and other views, the numerous tiles then assuming substantially the same relation as shingles secured upon a vertical surface. This overlapping inclined positioning is advantageous for water shedding purposes and it does away with the necessity of recessing the rear sides of any of the tiles to receive the upstanding flanges of underlying tiles, providing a construction which is less expensive to manufacture, yet will fulfill all demands. Regardless of the inclination of the flanges 24 and the entire rear sides of the tiles, the front faces of the brick-simulating portions 22 will be vertically disposed on a finished wall, due to the upward divergence of these faces with the rear sides 100 105 110

of the tiles. The brick-simulating portions 22 contact tightly with the flanges 24 of the underlying tiles and the steps 23 between brick-simulating portions, effectively represent mortar, for which purpose they may be of different color or otherwise differentiated from the brick-simulating portion. Moreover, in this connection, it may be explained that the steps 23 may be shaped 10 to represent any desired kinds of mortar joints and that the front faces of the portions 22 may be of such character as to represent practically any kind of brick.

The flange 24 of tile A is formed with 15 an appropriate number of nail-receiving openings 26 whose outer ends may be countersunk if desired, and it will of course be understood that the tiles may be nailed to new or old wooden structures, regardless of 20 the type of sheathing or weather-boarding with which they are provided.

Figs. 8, 9 and 10 show a tile usable at an internal corner and having about the same characteristics as the tile A, so that specific 25 description of all such characteristics is not necessary. It may be pointed out, however, that whereas one end of this tile is at right angles to the lower edge of the brick-simulating portion 22^a, the other end 25^a of said tile is at an obtuse angle to said edge. Then too, the mortar-simulating step 23^a extends only along the upper edge of the brick-simulating portion 22^a.

Figs. 11, 12 and 13 showing the tile C, 30 disclose the same relation between brick-simulating portion 22^b and flange 24^b, as above described, and the general shape of the tile in front elevation, is very similar to the tile B shown in Figs. 8, 9 and 10. The 35 mortar-simulating step 23^b however extends along the upper edge and one end of the brick-simulating portion 22^b. The opposite end 25^b of the tile is inclined, and at this end, a lateral flange 27 is provided integral 40 with the flange 24^b, the outer edge of said flange 27 being in the same plane with the front face of the brick-simulating portion 22^b. When this tile is in position upon a 45 wall, it occupies the position shown in Fig. 50 12. Hence, while the rear side of the tile is inclined, the outer edge of the flange 27 is flush with the brick-simulating portion 22^b to abut the adjacent end of another tile, it being understood that the tile C is used in 55 an internal corner.

The tile D as shown in Figs. 14, 15 and 16, is of right angular form in horizontal section and is provided with a long reach 28 and a short reach 29, each reach having 60 a brick-simulating portion 22^c, a mortar-simulating step 23^c, and an attaching flange 24^c. The steps 23^c extend along the upper edges of the portions 22^c and down the outer end of said portion of the short reach 29.

65 The tile E as shown in Figs. 17, 18 and

19 is practically a reversal of the construction shown in Figs. 14, 15 and 16, and the mortar-simulating step 23^d extends along the upper edges of the brick-simulating portions 22^d and down the outer end of said portion of the long reach 29^d.

The tile F, shown in Figs. 20 and 21 is substantially a duplicate of the tile A, the principal distinction being that the mortar-simulating step 23^e extends down both ends 75 of the brick-simulating portion 22^e as well as along the upper edge thereof.

The various tiles may be related as shown in Figs. 1, 2, 3 and 4 or in other adequate ways to meet the conditions encountered, and 80 in all instances, a weatherproof and attractive wall will be produced, in which the resemblance to brick is so marked that it is almost impossible to observe the difference. The tiles herein disclosed will cope with any 85 ordinary conditions which are encountered, but as above stated, special tiles may be made for use under unusual circumstances. Then too, minor variations may of course be made in the detailed construction of the 90 tiles and they may be formed of any desired plastic material, of glass, or of metal, as desired.

We claim:

1. A veneer tile having a lower brick-simulating portion which increases gradually in thickness from its lower to its upper edge, and a relatively thin attaching flange integral with and projecting upwardly from said brick-simulating portion, the rear faces of 95 said brick-simulating portion and flange being in a common plane which is inclined when the tile is attached, disposing the front face of the brick-simulating portion in a vertical plane, the front face of said flange 100 being rearwardly offset from said front face of the brick-simulating portion and disposed in a plane parallel with that in which the rear side of the flange is disposed, whereby the inclined side of the brick-simulating 105 portion of an overlying tile may lie tightly against said front side of said flange.

2. A veneer tile whose rear side is in a common plane at all extremities and is inclined when the tile is applied, the front 115 side of said tile being stepped to provide a brick-simulating portion, a mortar-simulating portion and a relatively thin upstanding attaching flange, the front face of said brick-simulating portion diverging upwardly 120 with the above named plane for vertical disposition when the tile is applied, the front face of said attaching flange being flat and parallel with said above-named plane, whereby the rear side of an overlying tile may 125 lie tightly against said front side of said flange.

3. A veneer tile having a lower brick-simulating portion gradually thickened from its 130 lower to its upper edge, a mortar-simulating

- step at the upper edge and one end only of said brick-simulating portion, and a flat up-standing attaching flange rearwardly offset from said mortar-simulating step, said flange having its front side parallel with its rear side and having the latter in the same plane with the rear side of said brick-simulating portion, both ends of the tile being substantially at right angles to the lower edge of 10 said brick-simulating portion.
4. A veneer tile having a lower brick-simulating portion gradually thickened from its lower to its upper edge, a mortar-simulating step along the entire upper edge of 15 said brick-simulating portion, and a flat up-standing attaching flange rearwardly offset from said mortar-simulating step, said flange having its front side parallel with its rear side and having the latter in the same plane 20 with the rear side of said brick-simulating portion, one end of said tile being steeply inclined at an obtuse angle to the lower edge of said brick-simulating portion, the other end of said tile being at right angles to 25 the lower edge of the brick-simulating portion.
5. A veneer tile having a lower brick-simulating portion gradually thickened from its lower to its upper edge, a mortar-simulating 30 step at the upper edge and one end only of said brick-simulating portion, and a flat up-standing attaching flange rearwardly offset from said mortar-simulating step, said flange having its front side parallel with its rear side and having the latter in the same plane 35 with the rear side of said brick-simulating portion, the end of the tile provided with the mortar-simulating step being substantially at right angles to the lower edge of said
- brick-simulating portion, the other end of 40 said tile being at an obtuse angle to said lower edge of the brick-simulating portion and being provided with a lateral flange projecting from said attaching flange, the outer edge of said lateral flange being in the 45 same plane as the front side of said brick-simulating portion.
6. A veneer tile of angular form in horizontal section with one long reach and one short reach, said tile having a lower brick-simulating portion gradually thickened from its lower to its upper edge, a mortar-simulating step at the upper edge of said brick-simulating portion and at the outer end of one of said reaches, and a flat upstanding attaching flange, said flange having the front sides of its two reaches parallel with the rear sides of said reaches and having said rear sides in the same plane as the corresponding sides of said brick-simulating portion. 50
7. A veneer tile having a lower brick-simulating portion gradually thickened from its lower to its upper edge, a mortar-simulating step at the upper edge and both ends of 55 said brick-simulating portion, and a flat up-standing attaching flange rearwardly offset from said mortar-simulating step, said flange having its front side parallel with its rear side and having the latter in the same plane 60 with the rear side of said brick-simulating portion, both ends of the tile being substantially at right angles to the lower edge of said brick-simulating portion. 65

In testimony whereof we have hereunto affixed our signatures.
